UNITED STATES PATENT OFFICE.

EMILIO PIERSANTELLI, OF TURIN, ITALY.

BOMB-THROWER AND BOMB TO BE THROWN THEREBY.

1,359,425.

specification of Letters Patent. Patented Nov. 16, 1920.

Application filed June 8, 1918. Serial No. 238,827.

To all whom it may concern:

Be it known that I, EMILIO PIERSANTELLI, a subject of the King of Italy, residing at Turin, Italy, have invented certain new and useful Improvements in Bomb-Throwers and Bombs to be Thrown Thereby; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention has for its object to provide an improved bomb thrower designed to be used instead of a rifle, and also an improved bomb designed to be thrown by the said improved bomb thrower.

20 Some constructional forms of the improved bomb thrower and of the bombs used therewith are illustrated by way of example in the accompanying drawings in which:

Figures 1 and 2 are respectively a side 25 view and a plan of a first example of the improved bomb thrower with automatic cocking mechanism;—Fig. 3 is a side elevation of a slightly modified form of the said bomb thrower;—Figs. 4 and 5 are longitudinal 30 sections of the automatic cocking mechanism and of the mechanism for releasing the striker, employed in the forms of the improved bomb throwers shown respectively in Figs. 1 and 3;—Fig. 6 is a longitudinal 35 section of a second example of the improved bomb thrower in which the cocking mechanism is entirely mechanical and designed to be operated by hand;—Figs. 7 and 8 show the cocking and releasing mechanism employed in the form shown in Fig. 6 in two 40 different positions of operation;—Figs. 9, 10 and 11 illustrate the improved bomb respectively in longitudinal section, side view and rear end view;—Fig. 12 illustrates a 45 detail;—Fig. 13 shows in detail a modification in the socket of the bomb.

A bomb thrower in accordance with the present invention (Figs. 1 to 3) comprises substantially a stock 1 preferably of wood 50 to the front end of which is fixed the barrel 2, and which ends rearwardly in a crescent-shaped butt 3, the ends of the crescent being preferably provided with sharp iron points 4. The barrel 2 is of suitable diameter to receive 55 the socket with which the bomb is provided; the said socket has an extension de-

signed to receive the cartridge for throwing the bomb as well as for actuating the time fuse of the bomb. Generally, the cartridge employed for this purpose is the usual rifle 60 cartridge. Inside the barrel there is mounted a striker 5 capable of sliding axially, (Fig. 2) and designed to act upon the percussion cap of the cartridge. This striker 5 is projected into its operative position by a 65 suitable spring contained in the rear portion of the barrel 2, and in the constructional examples of the bomb throwers shown in Figs. 1 to 5 said striker is cocked the first time by hand and afterward automatically 70 by the action of the gases generated by the ignition of the cartridge charge; these gases then effect the throwing of the bomb. The said striker may also be arranged to be cocked each time by hand and in such a case, 75 suitable cocking means must be provided that are capable of being operated by hand, as is the case in the bomb thrower shown in Figs. 6, 7, 8 and hereinafter described. The release of the striker is effected by any suitable mechanism, for instance by means of the rotary trigger 6 the several arms of which are operated successively by the operator.

Figs. 4 and 5 of the accompanying drawings show in detail two constructions of the automatic mechanism for cocking the striker as it is applied to the forms of bomb throwers shown in Figs. 1 and 3 respectively.

In the first of these examples (Fig. 4), 85 the barrel 2 is screwed onto a screw-threaded sleeve 2' fixed to the end of the stock 1. The striker 5 is slidably guided by means of the piston-shaped head 5' which extends rearward and ends in the engaging cone 5''. The spring 8 is guided inside the sleeve 9 which is fixed to the striker, and surrounding a rod 10 screwed to the sleeve 2'. Said spring has a constant tendency to push the whole of the striker toward the diaphragm 2'' which has a central hole through which the head of the striker 5 penetrates in such a manner as to act upon the percussion cap of the cartridge 20. The said diaphragm 95 may be pierced with small holes 2'''. The striker in its cocked position is engaged by the catch 11 which is mounted inside a suitable block 12, fixed to the barrel, and is pressed by the spring 11' toward the interior of the barrel into which it enters with its 100 beveled head. The return of the catch 11, 110 for the purpose of effecting the release of

the striker, is produced by means of the wedge-shaped bolt 13 which is mounted so as to be capable of sliding longitudinally in the block 12 and passes through a suitable 5 slot in the catch 11. This bolt 13 is constantly pressed into its position of rest by the spring 15 and is controlled by the rod 14 which is jointed thereto and which extends longitudinally inside the sheath 7 along the 10 lower part of the barrel 2 and the stock 1. Said rod is pivoted by means of an eye to an arm of a lever 16 which bears normally against a screw-adjusted stop 17. The other arm of the lever 16 is adapted to engage 15 with the arms of the rotary trigger 6 which is capable of rotating in the direction of the arrow (Fig. 4) and is prevented from rotating in the opposite direction by the elastic pawl 18 that engages the teeth of a ratchet 20 wheel 19 fixed to the rotary trigger.

The bomb 24 may be of any suitable construction. Its characteristic feature consists in a socket 22 provided at the rear designed to be slipped into the barrel 2 25 and to fit therein tightly by means of the annular packing 22^a with which it is provided. The socket 22 is hollow and is provided with a projection in the form of a sleeve 21 in which the cartridge 20 is placed. 30 This sleeve is fixed to the socket 22 by means of the end 21^a which is suitably perforated so as to establish communication between the interior of the socket 22 and the interior of the barrel 2. The bottom 35 of the cavity of the socket 22 contains the percussion cap 23 for igniting the time fuse of the explosive charge of the bomb.

The whole of the bomb has preferably the form shown in Figs. 9 to 11. By this 40 form the connection of the sleeve 21 to the hollow socket 22 is effected preferably (Fig. 11) by means of three thin arms 21^a preferably of wedge-shaped cross section, so that the gases of combustion of the cartridge 45 charge can pass freely from the cavity of the socket into the bore of the barrel 2.

The upper end of the socket is screw-threaded at 22^b. It is to this screw-threaded portion that the bomb proper 24 is connected by screwing, so that the latter can be 50 changed easily and quickly or replaced by another bomb when required.

The bomb 24 may of itself be of any type and size; it contains at least (Fig. 9) the 55 explosive charge 24^a and the time fuse 24^b which is fixed to the diaphragm 24^d. The fuse terminates outwardly in a deflagrating head situated facing the percussion cap 23 that is intended to be exploded by the action 60 of the bullet of the cartridge 20 which strikes it and which is adapted to be fitted in the orifice in the end of the socket 22 wherein the percussion cap 23 is itself mounted. At its inner end the fuse 24^b may 65 terminate in a detonator 24^c in the case

where such latter is required by the nature of the explosive. In order to assure a uniform combustion of the fuse 24^b, one or more holes 22^c for the passage of air, are formed in the head of the socket 22.

The tight-jointing of the bomb socket in the barrel of the weapon is in general sufficiently assured by the packings 22^d. However, if for any reason it should be necessary to have a more effective tight-jointing, 70 recourse may be had to the arrangement illustrated in Fig. 13. In this arrangement the socket 22 is provided with a ring of springs 40' fixed at one end to a collar 40 and mounted like the latter in a recess in 80 the socket 22. When the socket is inserted into the bore of the barrel, these springs 40' bear against the latter and thus provide an extremely effective jointing. The collar 40 with its springs 40' may be formed as 85 shown in Fig. 12 by being cut out from one piece which is then fixed by beading or folding over on the socket 22.

In the constructional example illustrated in Fig. 5, the mechanism for engaging the 90 whole of the striker is situated centrally and consists of three spring hooks 25 fixed to the block 27 which is fixed in its turn to the sleeve 2'. These hooks 25 are inclosed in the sleeve 9 upon which there is mounted 95 the spring 8 that acts upon the whole of the striker. In this arrangement the cone 5'', serving to effect the engagement of the striker when the latter is pushed to the rear, is sufficiently small to pass between the teeth 100 25' of the hooks 25 which will be temporarily moved apart, whereupon the cone 5'' will be held between the teeth 25' and will hold the striker in its cocked position. The release of the striker is produced in this 105 arrangement very similarly to that in the example described, by acting upon the rotary trigger 6 by means of the operating rod 14 which is provided at its end with a conical member 26. This member 26 by 110 acting upon the central portion of the spring hooks 25, moves the latter apart and thus produces the disengagement of the teeth 25' from the cone 5''.

The manner in which the improved bomb 115 thrower according to the example shown in Figs. 1 to 5 is to be employed and in which it operates is as follows:—

The striker is cocked by pushing it down into the cocked position, this being done by 120 the use of for instance a rod inserted through the barrel 2 until it comes into contact with the striker head 5. The bomb, provided with the cartridge 20 as shown in Fig. 4 is then mounted on the barrel 2 by 125 inserting the socket 22 into the bore of the barrel. The weapon can then be fired either by the operator placing the same against his shoulder in the same way as in the case of an ordinary rifle, or by holding 130

it in both hands, or by resting it with its points 4 upon the ground and aiming it at the desired angle. On the cartridge exploding, the bullet will strike the percussion cap 23 and produce the ignition of the time fuse of the explosive charge of the bomb, while the gases of the cartridge charge will act upon the inner end of the cavity of the socket 22 and upon the dia-
phragm 2'', and passing through the central hole in the latter and through the additional holes 2''', will act upon the piston 5'. Thus the said gases produce on the one hand the throwing of the bomb and on the other hand they cause the recoil of the whole of the striker which is thereby returned into the cocked position by engaging with the holding means constituted by the catch 11, or by the teeth 25' of the springs 25 according as to whether the bomb thrower is of the type illustrated in Fig. 4 or that illustrated in Fig. 5. The recoil of the whole of the striker is limited by the fact that the said whole will strike either against the rod 10 (Fig. 4) or against the mouth 10' of the sleeve 9 (Fig. 5). In both cases the striker is cocked automatically and when another bomb is to be thrown, it is merely necessary to insert the latter into the barrel 2 and to operate anew the trigger 6.

The improved bomb thrower according to the second example shown in Figs. 6 to 8, comprises as usual the stock 1 preferably of wood, to the front end of which the barrel 2 of the weapon is fixed by screwing on the sleeve 2'. The rear part of the stock is preferably straight and ending in a sharp point 4 which may serve as a support in the ground; it is preferably fixed in a removable manner by screwing on the stock 1 and serves as a plug for closing the recess 1^a that is intended to serve as a container for any accessories for the weapon.

The striker 5 extending through the dia-
phragm 2'' of the barrel, is slidably mounted by means of its enlarged rear part 5' in the part of smallest diameter 2^a of the barrel, while by means of its rod 5^a slidably mounted in a suitable longitudinal hole in the stock 1, it is connected to the cocking and releasing mechanism hereinafter described. A coiled spring 8 is provided inside the part of smallest diameter 2^a of the barrel and bears at one end against the part 5' of the striker and at its other end in the mortise 2^b in the end of the sleeve 2'. This spring serves to push the striker proper into its operative position.

The cocking and releasing mechanism which is adapted to be operated by hand is arranged in the box 30 fitted in a suitable mortise provided near the middle of the stock 1, and is fixed therein by any suitable means, for instance by screws 31. This mechanism consists of two levers 32, 33 ful-

crumed on the same pivot 34 that is fixed to the box 30. The upper end of the lever 32 has the form of a fork 32' in which engages the suitably shaped end 5^b of the rod 5^a. By means of a suitable coupling, the lever 32 is positively connected to the lever 33 only when it rocks in a determined direction. This coupling may be constituted for instance by providing the lever 33 with a nose 33' which by the action of a leaf spring 35 fixed to the lever 32, fits in a lateral recess in the said lever 32. By this arrangement the lever 33 is able to operate the lever 32 in the direction of rotation necessary for exerting a pull upon the rod 5^a, whereas it is free to rotate in the opposite direction without actuating the lever 32 in opposition to the elastic resistance of the leaf spring 35.

The lever 33 is further provided with a radial tooth 33'' designed to be actuated by the operating lever which is mounted so as to rock upon a pivot 36 fixed to the box 30 and projects to the outside in the form of a finger-piece 6 adapted to be operated by the hand of the marksman. Its other end inside the box 30 terminates in a tooth 6' designed to engage the tooth 33' of the lever 33. The operating lever has a constant tendency to be moved in the direction of the arrow —a— (Fig. 6) by elastic means which may consist for instance of a coiled spring 37 fixed at one end to the box 30 and bearing with its other end against the operating lever.

The operation of the above described bomb thrower according to the second example and having a cocking destined to be operated by hand, is as follows:

On the marksman pressing with his hand upon the finger-piece 6 in such a manner as to cause it to turn in the direction of the arrow —b— (Fig. 6), the tooth 6' will press against the tooth 33'' of the lever 33 and will cause the latter to turn, and by means of its nose 33' to move with it the lever 32, and thereby exert a pull upon the rod 5^a of the striker, the result being to compress the spring 8. As soon as the position shown in Fig. 7 has been reached, the tooth 6' will become disengaged from the tooth 33'', so that the levers 32 and 33 as a whole will be released to the rear by the action of the spring 8 which has been previously stressed, while the striker 5 is violently impelled and strikes (Fig. 9) the percussion cap of the cartridge 20 mounted in the sleeve 21 of the socket 22 with which the bomb 24 is provided, thereby effecting the throwing of the said bomb. To restore the weapon into condition to repeat the above described working, it is merely necessary to let go the finger-piece 6. Then the latter under the action of the spring 37 moves back again and acting with the back of its tooth 6' upon the back of the tooth 33'', it causes the lever 33

33 to rock as shown in Fig. 8 until after having moved past the tooth 33", the said lever 33 will be returned by the spring 35 in the direction of the arrow Fig. 8 into the 5 position shown in Fig. 6 wherein its tooth 33" can be actuated anew by the tooth 6' on the subsequent operation of the finger-piece 6, and so on.

By means of the above described mechanism the cocking of the weapon is thus effected by hand a few instants before it is released, and by means of the same member that effects the release. In the second example of bomb thrower therefore the gases 15 generated by the explosion of the cartridge charge have no function beyond that of throwing the bomb.

The improved bomb thrower owing to the simplicity of its construction is cheap to 20 make, while its throwing efficiency is much greater than that which can be obtained with the ordinary rifle with which it can be compared as regards ease of transport and use. Another rather important characteristic 25 feature consists in that it uses the ordinary rifle cartridges, while the bomb by reason of its special construction which renders it capable of being thrown with the improved bomb thrower, is absolutely de- 30 void of risk before being thrown, whether it be fitted with a cartridge or not, this feature being very advantageous both as regards 35 transport and handling.

Although the weapon forming the subject 35 of the present invention is more particularly designed for throwing bombs, it is however to be understood that the said weapon may be used also for throwing any object or casing screwed on the screw-threaded end 40 22^b of the socket 22 (Fig. 9) in place of the bomb proper.

The hereinabove described weapon is provided preferably either with a bayonet permanently fixed thereon and adapted to be 45 folded back into an inoperative position when it is not required for use, or with a fastening device for the attachment of the usual bayonet.

The hereinbefore described weapon, especially when provided with a bayonet, is a full and advantageous substitute for the usual rifle in modern combats. This weapon has in fact all the characteristics of a portable weapon and consequently of a weapon 55 of assault either for attacking or for giving very intensive fire by bombing. The rifle which has become henceforth a weapon having over-sufficient ballistic properties, and at the same time insufficient as regards quantity and efficiency of fire, may be replaced to advantage by the present improved weapon which is much more simple, cheaper and comprises in itself the necessary qualities for throwing the present infantry projectile, 60 that is to say, the bomb that has hitherto

been thrown by hand. This weapon which constitutes substantially a rifle without ballistic requirements solves in a perfect manner the problem of throwing the bomb, while all the experiments made hitherto in this 70 direction have been directed toward the possibility of converting the usual rifle into a bomb thrower, and have encountered the difficulty of having the cartridge, that is to say, the charge for throwing the bomb, 75 separated from the actual bomb by an obstacle such as the barrel of the rifle, so that it was not possible to utilize the whole efficiency of the cartridge, that is to say, of the charge and of the bullet. Now on the contrary in a weapon according to the present invention the striker and the cartridge have been transferred substantially from the rear portion to the muzzle of the weapon in such a manner that the cartridge being freed 80 from the obstacle that was constituted by a ballistically delicate and exact device, such as the rifle barrel, can be better and completely utilized for throwing and for automatically igniting the bomb. 85

It is to be understood that this invention is not limited in any way to the precise arrangements described and shown, and that without departing from the nature of the invention they can be modified in any way 90 that may be found necessary or desirable by the requirements or circumstances of practical use.

I claim—

1. A bomb thrower comprising a barrel, 100 percussion mechanism operating near the end of the barrel in combination with a bomb having a rearward tubular socket to fit into the end of said barrel and a cartridge holder extending from the end of said 105 socket to hold a cartridge in firing relation to said percussion mechanism.

2. A bomb thrower comprising a rifle barrel, a socket adapted to be mounted in the muzzle of the barrel and support, a bomb at 110 the end thereof, means for supporting a rifle cartridge in the socket, and a striker in the barrel adapted to explode the cartridge, whereby the exploding cartridge charge will throw the bomb and the cartridge bullet explode the latter. 115

3. A bomb thrower comprising a short gun barrel, a stock therefor, a socket member for insertion into the barrel having a prolongation adapted to receive a rifle cartridge, a striker slidably mounted in the barrel and adapted to act upon the percussion cap of the cartridge, said cartridge constituting the charge for throwing the bomb, and means for cocking and releasing the 120 striker. 125

4. A bomb thrower comprising a stock having a butt, a short gun barrel fixed to the front end of the stock, a socket for supporting a bomb adapted to fit into the muzzle of 130

the barrel, an extension fixed in the socket to receive a rifle cartridge, and a striker slidably mounted in the rear portion of the barrel and adapted to act upon the percussion cap of a cartridge mounted in said extension, said cartridge constituting the charge for throwing the bomb, and means for cocking and releasing the striker.

5. A bomb thrower comprising a barrel, 10 percussion mechanism operating near the end of the barrel in combination with a bomb having a rearward tubular socket forming a gas chamber fitting into the end of said barrel, a cartridge holder extending 15 from said socket for presenting a cartridge to said percussion mechanism, said gas chamber vented to the rear thereof.

6. A bomb thrower having a barrel and an automatic cocking firing mechanism, in 20 combination with a bomb having a socket extension at the rear forming a gas chamber and fitting the end of said barrel, and a cartridge holder extending from said socket member for presenting the cartridge to the 25 percussion member, said socket member

vented into the barrel to effect the cocking of the firing mechanism.

7. A bomb thrower having a barrel and an automatic cocking firing mechanism, in 30 combination with a bomb having an explosive charge chamber, a fuse chamber connected to the latter by a fuse, a socket member closing the fuse chamber and having an opening in line with said fuse, said socket member fitting the end of said barrel and 35 having rearwardly directed vents, and a cartridge holder extending from said socket member and of smaller diameter to present a cartridge to said firing mechanism, whereby the gases from said cartridge and from 40 said fuse chamber will be vented from the socket member into said barrel to cock the automatic firing mechanism.

In testimony that I claim the foregoing as my invention, I have signed my name in 45 presence of two subscribing witnesses.

EMILIO PIERSANTELLI.
